HYDRAULIC WELL BORING ARRANGEMENT
FOR ROTARY JUMPER METHOD OF BOR-
ING

Maurycey Ringler, Walbrzych, Poland

Application August 18, 1949, Serial No. 111,058

6 Claims. (Cl. 255—38)

1

The present invention relates to well drill gear as used in connection with the drilling of oil wells. More particularly, the invention relates to well drill gear of the jumper type in which by means of a fluid under pressure a rotary and an up and down movement is imparted to the cutting tool assembly of the drill gear, the power required for operating the drill gear being supplied by a power unit such as a hydraulic motor.

One object of the present invention is to provide control means which permit a convenient and efficient control of the power unit and of the quantity and the distribution of the rinsing liquid generally employed in connection with drilling operations. As a result, the drilling operations can be conducted in accordance with the specified properties of the strata through which a well is drilled.

Another object of the invention is to provide a drill gear of the general type above referred to which permits an efficient clearing of obstructions encountered by the head of the drill during the drilling operation. More specifically, the drill gear according to the invention permits to direct the fluid under pressure so that it is directed partly to the power unit and partly into the drill hole bypassing the power unit or the entire fluid is directed into the drill hole for rinsing the same.

Another object of the invention is to provide a drill gear which permits to direct the rinsing fluid so that it does not spill on the floor of the drill derrick when the drill gear is pulled up.

Other and further objects, features and advantages of the invention will be pointed out herein-after and set forth in the appended claims forming part of the application.

In the accompanying drawing a now preferred embodiment of the invention is shown by way of illustration and not by way of limitation.

In the drawing:

Fig. 1 is a sectional view of the upper part of a drill gear according to the invention.

Fig. 2 is a sectional view of the middle part of the drill gear.

Fig. 3 is a sectional view of the lower part of the drill gear including the cutting assembly.

Fig. 4 is a section taken on line 4—4 of Fig. 3.

Fig. 5 is a section taken on line 5—5 of Fig. 1.

Fig. 6 is a section taken on line 6—6 of Fig. 1.

Fig. 7 is an enlarged fragmentary sectional view of the upper part of the drill gear showing the control means for the gear in one limit position.

Fig. 8 is a sectional view similar to Fig. 7 but showing the control means in an intermediate position, and

2

Fig. 9 is a sectional view similar to Fig. 7 but showing the control means in the other limit position.

Before describing the figures in detail it should be mentioned that Fig. 2 should be visualized as a continuation of Fig. 1 and that the drill gear is in vertical position when in operation, the right hand end of Fig. 1 constituting the top of the drill gear and the left hand end of Fig. 2 the bottom end of the drill gear. In the subsequent description it is assumed that the drill gear is in the aforementioned position.

Referring now to the figures in detail the entire drill gear with the exception of the drill head 1 is encased in a shell 6. A bush 61 is secured to the top end of shell 6. A hollow control member 57 is rotatably and axially displaceably inserted in this bush as will be more fully explained hereinafter. Member 57 also serves as conduit for the admission of fluid under pressure and is provided for this purpose at its outer end with a conical thread 58. The fluid under pressure is fed to the drill gear by connecting a conduit of suitable design to member 57. The portion of bush 61 within shell 6 is widened and provided with an internal thread. A member 48 is threaded in this thread. This member serves as the stationary valve body of a control valve the movable component of which is controlled by member 57. Member 48 supports a sleeve composed of sections 19, 28 and 42 joined by fittings 25 and 41. The top section 42 is fixedly secured to member 48. The entire sleeve 19, 28 and 42 is disposed coaxially with shell 6 spaced therefrom so as to form an annular space 29 for the passage of the rinsing fluid. The top portion 42 of the sleeve forms a cylinder for a piston 43 slidably seated therein by means of packings 44. Piston 43 is slidably supported on a pipe 46 by means of a packing 45. This pipe is continued in a centric bore of member 48. The rod of piston 43 is formed by a pipe 70 which leads to a power unit 33 of conventional design such as a hydraulic motor. This power unit includes a sleeve 30 slidable relative to the component of the power unit secured to pipe 70. This sleeve includes inlet and outlet ports for the fluid and is sealed by means of a packing 36. The slidable sleeve coacts with a flexible stop 27 when it reaches its lowermost position. This stop is disposed within sleeve section 28. The sleeve 30 can move relative to piston 43 between the aforementioned lowermost position and an uppermost position in which it is stopped by a second flexible stop 39. When the sleeve is in its uppermost po-

sition rinsing fluid such as diluted loam can be fed through channel 35 to the power unit. As can best be seen on Fig. 2, channel 35 may then be in registry with a corresponding port in sleeve 30. As a result, the supplied fluid enters the space below the piston thereby lifting the same. Lifting of the piston effects also lifting of pipes 21, 20 and the drill head 1. The lifting of the piston is continued until the power unit is stopped by the upper stop 39 whereupon the sleeve 30 is shifted down with respect to piston 43. In its lower position sleeve 30 closes channel 35 and opens a channel 34 whereby the fluid trapped in the passage-way of member 10 above channel 35 forces the piston down while the fluid in the cylinder 42 below piston head 43 discharges through channel 34 and the longitudinal passages in members 20, 21 and drill head 1. When piston 43 reaches its lowermost position, sleeve 30 strikes stop member 21, is raised to its open position and the cycle is repeated.

The bottom part of shell 6 supports a threaded ring 5 which is composed of two sections. This ring forms an inwardly protruding portion 3 which serves as a catch for the drill head in case the shank thereof is unscrewed or broken during a drilling operation. For this purpose a collar 1a is provided which cannot pass through portion 3.

Referring now to the control means for controlling the operation of the drill gear, there is shown a valve member 51 threaded upon control member 57. This member 51 is hollow and is formed with a lower conical surface and an upper conical surface. The circumference of member 51 includes six guide grooves engageable by a screw 59 for the purpose of preventing a rotation of member 51 but allowing a vertical displacement of the same. Member 51 includes ports 50 which communicate with the interior of control member 57. The lower portion of the member coacts with a valve seat 49 formed by member 48. The upper portion of member 51 cooperates with a valve seat 52 formed in bush 61. This valve seat 52 communicates through channels 53 and 54 with channel 29 formed between the sleeve and the outer shell.

In the position of control member 57 and of member 51 as shown in Figs. 1 and 7, the lower cone of member 51 is separated from valve seat 49 and the upper cone presses against valve seat 52. As a result, fluid can flow through ports 50 into pipe 46 thereby feeding the full flow of the operational fluid to the power unit. The flow of fluid to channel 29 for the rinsing fluid is cut off by the upper cone of member 51. When member 57 is moved downwardly into a position of Fig. 9 in which the lower cone of member 51 is seated upon seat 49, the flow of fluid through ports 50 is cut off and channels 53 and 54 are opened. Consequently, the entire fluid is supplied to channel 29 and the power unit is stopped. In the intermediate position of members 57 and 51 as shown in Fig. 8 all the aforementioned ports and channels are open so that part of the fluid is supplied to the power unit and part to channel 29.

As will be apparent from the previous description, cone member 51 in which member 57 is threaded can be axially moved by rotating member 57 in bush 61.

The hereinbefore described control of the admission of fluid under pressure permits to direct the entire flow of fluid into channel 29. From this channel the fluid flows from bores 4 into the well thereby washing out any obstructions preventing

an operation of the drill head or any other part of the drill gear. As will be apparent from the previous explanation, the power unit is stopped when the entire rinsing fluid is directed into the channel. As soon as the obstruction has been removed the power unit is started again by turning control member 57 into a position in which at least part of the fluid is fed to the power unit. By regulating the portion of the fluid fed to the power unit the speed of the up and down movements of the cutting assembly of the drill gear can be conveniently regulated.

Control member 57 is provided with upwardly protruding teeth 57a which coact with downwardly protruding teeth 60 of bush 61. Engagement of teeth 60 and 57a prevents a rotation of control member 57 during a drilling operation. As will be apparent, the drill gear hangs with its full weight on the teeth thereby pressing the same together. When it is desired to rotate member 57 for varying the distribution of the flow of fluid the drill gear is lowered to the bottom of the drill hole. As a result, the teeth are relieved of the weight of the gear and the control member 57 can be easily rotated.

In case the drill head or the conduit bar connected to control member 57 is jammed by an obstruction, member 57 can be lowered by lowering the conduit bar connected thereto. As is previously explained, a lowering of member 57 opens channels 53 and 54 thereby admitting fluid into channel 29 from where it reaches the drill hole through bores 4.

To prevent lifting of fluid to the top of the drilling hole when it is desired to lift the drill gear for instance for inspection the gear is first lowered to the bottom of the drill hole and then channels 53 and 54 are opened by turning control member 57 in the appropriate direction. Rinsing fluid can now freely pass through channel 29 and bores 4 of the drill gear.

For the purpose of rotating cutting head 1 during a drilling operation, sleeve section 19 is connected at its lower end with a pipe 18 by means of shock absorbing elements 8, 9, 10 and 11. This pipe 18 is secured at its upper end to a pipe 20 operatively connected with the power unit and the lower end of pipe 18 is operatively connected with the cutting head 1. The outer wall of pipe 18 is formed with slanted grooves 16 engaged by lugs 15 of a ring 13. This ring has on its periphery ratchet teeth which coact with two pawls 12. These pawls retain ring 13 during the downward movement of pipe 18 and permit rotation of pipe 18 in unison with the cutting head through an angle of a few tenths degrees during each part movement of the cutting assembly.

What is claimed, is:

1. In a well drill gear of the jumper type in which by means of fluid under pressure a rotary and an up and down movement is imparted to a cutting tool assembly, a shell, the bottom end of said shell guiding the cutting tool assembly, the operating fluid being admitted at the top end of said shell, sleeve means fixedly mounted within said shell concentric therewith, a power unit for the cutting tool assembly mounted within said sleeve means, said shell and said sleeve means forming an annular channel therebetween open at the bottom end of the shell near said cutting tool assembly, and valve means at the top end of the shell for selectively directing the operating fluid either to said power unit or to said channel for use as rinsing fluid or

partly to the power unit and partly to said channel, the said valve means comprising a stationary valve body secured to said sleeve means and formed with a port in communication with the power unit and with a port leading to said annular channel respectively and a movable hollow valve body having outlet ports mounted in the shell axially displaceable relative to the stationary valve body and communicating with a supply of fluid under pressure, the said movable valve body closing in one position the ports communicating with the power unit and in another position the ports leading to the annular channel and in a position intermediate to the said two positions opening all the ports for the purposes aforesaid.

2. A well drill gear as defined in claim 1, wherein pipe means are secured within said sleeve means coaxially therewith leading from the top of the sleeve means to the power unit and supporting said cutting tool assembly, the top end of said pipe means communicating with the respective port in said stationary valve body, and wherein said movable valve body comprises a fluid inlet member mounted at the top end of the shell axially displaceable relative to the shell, said member having said outlet ports for discharge therefrom of the pressure fluid fed to the inlet member from the source of supply, the bottom end of the inlet member forming a first valve member adapted to be seated upon said port communicating with the pipe means for closing the ingress of fluid into the pipe means, and an intermediate portion of the inlet member forming a second valve member, said second valve member controlling the port of the stationary valve body leading into said annular channel, the said valve members and the said ports of the movable and the stationary valve body being disposed in a relative position in which the channel ports are covered by the second valve member when the first stationary valve member is seated upon said valve body and are uncovered when the inlet member is axially lifted into a position above said stationary valve body.

3. A well drill gear as defined in claim 2, in combination with a guide bushing secured to the top end of said sleeve means, the said bushing being formed with internal threads and the said inlet member being formed with external threads engaging each other for axial displacement of

said inlet member by rotating the same, said bushing further having external upwardly extending teeth, a second bushing secured to the top end of said pipe means and having downwardly extending teeth engageable with said teeth of the first bushing, substantially the entire weight of the drill being suspended on said two sets of teeth for preventing rotation of the inlet member relative to the bushing during the drilling operation, whereby resting of the cutting tool assembly upon the bottom of the well relieves the axial pressure between said teeth thus permitting rotation and axial displacement of the inlet member for the purpose of varying the positions of the valve members supported thereon relative to said stationary valve body and the respective ports.

4. A well drill gear as defined in claim 3, wherein the said sleeve means extend from said power unit to the cutting tool assembly, and wherein shock absorbing means are included in said sleeve means between the power unit and the cutting tool assembly.

5. A well drill gear as defined in claim 4, wherein said sleeve means between the power unit and the cutting tool assembly comprise two pipe sections, and wherein unilaterally acting locking means connect said two pipe sections, said locking means including a slanted guide groove in one pipe section and a lug extending from the other pipe section and engaging said groove so as to impart a limited rotary movement to the cutting tool assembly for each up and down movement thereof.

6. A well drill gear as defined in claim 1, wherein the bottom end of said shell is provided with inwardly extending flange means, and wherein said cutting tool assembly includes an outwardly protruding portion wider than the shell opening and said flange means for retaining the cutting tool assembly within the shell in case the said assembly becomes separated from its support during a drilling operation.
